SQUARE CAN SEAMING HEAD

Otto A. Schmitt, Jersey City, N. J., assignor to
 Continental Can Company, Inc., New York,
 N. Y., a corporation of New York

Application June 28, 1943, Serial No. 492,580

4 Claims. (Cl. 113—24)

1

The invention relates generally to the art of can making and primarily seeks to provide certain new and useful improvements in seaming head structures adapted for double roll seam securing end closures on can bodies which are oblong or generally square in shape.

More particularly, the invention seeks to provide certain new and useful improvements in seaming head structures of the type disclosed in U. S. Letters Patent 2,271,152 and 2,271,153 issued on January 27, 1942 to Alfred L. Kronquest and jointly to the said Kronquest and Otto A. Schmitt. These patented seaming head structures were designed with the purpose in view of assuring the formation of seams which were uniformly tight throughout the whole periphery of the square or oblong can bodies, much difficulty having been experienced theretofore in providing seam structures which were satisfactorily tight at all corners. Said patented seaming head structures each include a rotor, a chuck member about which the rotor rotates and which is surrounded by a positioning lever guiding groove, four positioning levers arranged in diametrically opposed pairs and each being pivoted at an outer end on the rotor and having a roller at its inner end guided in said groove, a seaming arm pivoted intermediate its ends on each said lever, two diametrically oppositely disposed arms being equipped with first operation seaming rolls at their inner ends and the other two arms being similarly equipped with second operation seaming rolls, and each said arm at its outer end being provided with a nose engageable by a cam positively rotated about the pivot center of the respective lever for at the proper time forcing the respective seaming roll against the chuck for effecting a seaming operation. While these patented seaming head structures operate satisfactorily and have provided marked advances in the art it has been found desirable to reduce the size of the heads and thereby materially reduce the mass weight and the amount of metal necessary to be employed in the manufacture of said heads. It has been found that the mounting of the seaming arm actuating rotary cams for rotation about the pivot centers of the positioning levers results in the provision of a much greater bulk of metal at the positions of said pivotal mountings, and a much greater overall diameter of the seaming head than would otherwise be necessary. It is a purpose of the present invention to provide an improved seaming head structure of the character stated in which the parts are cooperatively arranged in a novel compact manner effective to

2

materially reduce the amount of metal necessary to be used in the seaming head structure and also the overall diameter of said structure.

An object of the invention is to provide a seaming head structure of the character stated in which each positively rotated cam effective to impart movement of one of the seaming arms toward the chuck is mounted to one side of the pivot center of the associated positioning arm and approximately at the same distance from the head center as said pivot center, thereby to materially reduce the overall diameter of the head and also shorten the necessary length of the respective levers.

15 Another object of the invention is to provide a seaming head structure of the character stated in which the outer end of each seaming arm is equipped with a large diameter roller which is engaged by the associated rotary cam for forcing the respective seaming arm carried seaming roll against the chuck, said cam and roller engagement serving to minimize wear and avoid the effective leverage length changes which attended the cam and seaming arm nose engagement in the patented seaming head structures hereinbefore referred to.

20 With the above and other objects in view that will hereinafter appear, the nature of the invention will be more fully understood by following the detailed description, the appended claims and the several views illustrated in the accompanying drawings.

In the drawings:

25 Figure 1 is a fragmentary vertical sectional view illustrating a seaming head structure embodying the invention.

30 Figure 2 is an inverted plan view of the seaming head shown in Figure 1, both second operation seaming arm actuating cams being broken away and one second operation seaming arm and positioning lever equipment being broken away.

35 Figure 3 is a fragmentary sectional view illustrating one lever and arm set and the associated rotary cam.

40 Figure 4 is a detail plan view of one of the second operation set rotary cams.

45 The herein disclosed seaming head structure may be stationarily mounted in a single seaming station machine or it may be one of a plurality of seaming heads carried by a rotor which rotates while the seaming operations are in progress. Such a machine is disclosed in the U. S. Letters Patent 1,752,912 issued to A. L. Kronquest on April 1, 1930, and it is the purpose of the present invention to provide certain new and useful im-

provements in seaming head structures of the type adapted for seaming square or oblong cans which render the heads so compact that as many as four thereof can be mounted on a single rotor.

When the seaming head structure is embodied in a machine in which a plurality of the heads are carried by a rotor it is employed in combination with a turret 5 which is rotatable with a hollow column 6 to which rotation is imparted by any approved means (not shown), said turret including peripheral pockets 7 for receiving the cans 8 which are to be positioned in cooperative relation beneath the seaming heads during the seaming operations. The usual vertically reciprocable supporting pads 9 are provided for supporting the cans in the turret pockets and for at the proper time lifting the cans into cooperative relation with the seaming devices and for lowering them after the seaming operations have been performed.

A casing 10 is supported on the column 6, and at the upper end of the casing there is provided a bearing portion 11 which is rotatable about a sleeve 12 depending from a knockout pad actuator cam 13, the latter being keyed as at 14 to a stationarily supported column 15.

A center drive shaft 16 is mounted within the column 6, and the upper end of this shaft is spline connected as at 17 to a drive sleeve 18 which is rotatable in anti-friction bearings 19 in an upstanding well 20 of the casing 10 and in anti-friction bearings 21 provided in the lower end of the bearing portion 11. The driver sleeve has a ring gear 22 and a ring gear 23 flange secured thereto as at 24 and the purpose of these ring gears will become apparent as the description progresses.

The upper end of the casing 10 also is provided with a bearing sleeve 25 in which a clamp bearing 26 is mounted. A support sleeve 27 is keyed as at 28 in the clamp bearing 26 and has its upper end supported, as by the screw clamp collar 29 on the upper end of the bearing sleeve 25. The sleeve 27 is provided with a plate enlargement 30 at its lower end, and to this enlargement is removably attached a guide and chuck mounting plate 31. A key 32 is inserted between the plates 30 and 31 and a chuck 33 is removably secured as at 34 to the plate 31. It will be observed by reference to Figures 1 and 2 of the drawings that the plate 31 is provided with a guide groove 35 which surrounds and follows the contour of the chuck which in this illustration is oblong in shape and provided with rounded corners.

The chuck 33 is provided with a bottom recess for receiving a knockout pad 36 which is removably mounted at the lower end of a knockout rod 37 which extends upwardly through the sleeve 27 and has a cross head 38 adjustably secured on its upper extremity as at 39. The cross head is provided with an actuator roller 40 which engages in an actuator groove 41 in the previously mentioned cam 13.

The plates 30 and 31 are disposed within a bottom recess 42 in a rotor 43 having anti-friction bearing as at 44 on the supporting sleeve 27 and including an upwardly extending sleeve portion 45 which surrounds the supporting sleeve 27 and has a driver gear 46 keyed on the upper end thereof as at 47.

A sleeve 48 is rotatable about the rotor sleeve extension 45, having bearing thereon as at 49, and the sleeve 48 has a driver gear 50 keyed on its upper end as at 51. The sleeve 48 has a ring gear extension 52 at its lower end.

At four equidistantly spaced points near its periphery the rotor is provided with bearings 53 in each of which is rockably mounted a shaft 54. Each shaft 54 is removably secured in its bearing as at 55 and has a positioning lever 56 extending inwardly therefrom in the manner clearly illustrated in Figures 1, 2 and 3 of the drawings. At its free end each lever 56 is equipped with a roller 57 which engages in the guide groove 35 for the purpose of causing the inner end of the lever to follow around the contour of the chuck as the rotor is rotated about the chuck. A seaming arm 58 is pivoted intermediate its ends as at 59 on each lever 56, and it will be observed by reference to Figures 2 and 3 of the drawings that the inner and outer ends of each seaming arm overlie the inner and outer ends of the respective positioning lever. Two of the diametrically oppositely disposed seaming arms 58 carry 10 two first operation rolls 60 at their inner ends, and the other two diametrically oppositely disposed seaming arms carry two second operating seaming rolls 61 at their inner ends. The several seaming rolls 60 and 61 are removably secured on the ends of the seaming arms by shoulder screws 62. At its other end each seaming arm 58 is bifurcated and equipped with a large diameter roller 63 mounted in and extending from the bifurcation. Each roller is engaged by a rotary cam 64 which is secured as at 65 on a shaft 66 rotatably mounted in a bearing 67 provided therefor in the rotor. It will also be observed by reference to Figures 2 and 3 of the drawings that each bearing 67 is in the form of an eccentric sleeve and that the shaft 66 rotatable therein is disposed beside and in parallel spaced relation to the adjacent positioning lever mounting pivot 54. Each of the cam shafts 66 is extended upwardly through its bearing and is equipped at 20 its upper end with a spur gear 68, all said gears being enmeshed with and driven by the ring gear 52 in the manner clearly illustrated in Figure 1.

The two diametrically oppositely disposed rotary cams 64 which are associated with the first operation seaming arms have the effective arcs 69 thereof provided with three steps 70, and the effective arc of the other two diametrically oppositely disposed second operation cams preferably have their effective arcs 71 equipped with two steps 72. It will be obvious that by adjusting the bearing sleeves 67 rotatably about their axes the cooperative relation of the respective cams and the seaming levers engaged thereby can be varied so as to properly position the respective seaming rolls.

It will be obvious by reference to Figure 1 of the drawings that the ratios of the enmeshing gear sets 22, 46 and 23, 50 varies so that during the rotation of the casing 10 and turret 5 about the axis of the shaft 16 differential speed rotation will be imparted to the rotor 43, 45 and the sleeve and ring gear unit 48, 52, thus causing the rotor to rotate about the relatively stationary chuck 33 and the several pinion gears 68 and the attached cams 64 to rotate on the rotating rotor. During rotation of the rotor the rollers 57 cause the inner ends of the positioning levers to follow the contour of the chuck 70 and thus always properly place the seaming rolls 60, 61 relative to the external surface of the chuck. Rotation of the cams 64 causes the first and second operation seaming rolls to be forced against the chuck for properly performing the seaming function, the first operation

cams serving to move the first operation seaming rolls against the chuck in three successive steps, and the second operation cams preferably serving to move the second operation seaming rolls against the chuck in two successive steps. The particular seaming head herein disclosed is designed to accomplish the seaming function in 200° of movement of the turret, leaving 160° for the introduction of the non-seamed cans into the turret, the lifting of the cans into co-operative relation with the seaming devices, the lowering of said cans and the removal from the turret of the seamed cans. This seaming function is accomplished with 2½ turns of a seaming head during which the before mentioned three step inward movement of the first operation seaming rolls is effected within 1½ turns of the head and the before mentioned two step inward movement of the second operation rolls is effected within one turn of said head.

During the rotation of the seaming head and the casing structure 10 about the axes of the center column the stationary cam 13 serves in the manner well known in the art to operate the knockout rod 37.

By positioning the cam shafts 66 beside the seaming lever pivots 54, close to the periphery of the rotor and at substantially the same distance from the rotor center as said lever pivots 54, the overall diameter of the seaming head is reduced to a minimum. It has been found that by this compact arrangement a seaming head twelve inches in diameter can be provided whereas with the previously known arrangement of the cooperating parts in the seaming head it was necessary to provide a head at least sixteen inches in diameter for performing the seaming operations on the same size cans. It will be obvious that this compact arrangement of parts results in the provision of a seaming head which is materially reduced in mass weight as well as size and that positioning levers and seaming arms of shorter length can be utilized. It has been found that a reduction of approximately thirty per cent in the mass weight of the seaming head can be provided by forming the seaming head in the manner herein disclosed.

It should also be apparent that in providing large diameter rollers 63 for engagement with the rotary cams 64 instead of the previously employed relatively sharp nosed cam followers engagement between cam surfaces and the seaming levers in a manner for maintaining constancy of leverage will be assured whereas in the previous uses referred to objectionable changes in effective leverage tended to decrease the efficiency of the seaming operations. The engagement of the cams with the large diameter rollers also avoids the considerable amount of wearing away of engaging surfaces which was experienced in the provision of cam followers of the type previously employed.

In order to properly maintain contact between the large diameter rollers 63 and the control cams with which they cooperate, the pin on which each said roller is mounted may be extended as at 73 and connected by a retractile spring 74 with an anchor pin 75 depending from the rotor 43 beside the respective control cam opposite the side of said cam engaged by the particular roller. See Figures 2 and 3.

It is of course to be understood that the details of structure and the arrangement of parts may be variously changed and modified with-

out departing from the spirit and scope of the invention.

I claim:

1. In a seaming head structure of the character described, a chuck surrounded by a guide groove following the contour of the chuck, a rotor rotatable about the chuck, a plurality of positioning lever each attached at its outer end to a shaft rockably mounted on the rotor for swinging movement about an axis which parallels the axis of the rotor, each said positioning lever carrying a roller at its inner end engaging in said guide groove, a seaming arm pivotally mounted intermediate its ends on each lever with the inner and outer ends of each said arm overlying the inner and outer ends of the respective lever, a seaming roll carried at the inner end of each arm for cooperation with said chuck, a rotary cam engageable with the outer end of each seaming arm and mounted on a cam shaft which is rotatably mounted on the rotor separate and apart from the rockably mounted shaft to which the positioning lever on which the particular seaming arm is mounted is attached and paralleling said rockably mounted shaft, the axes of both said shafts lying side by side in the direction of rotation of the rotor and the cam shaft axis being spaced from the rotor axis a distance approximately the same as the distance of said rockably mounted shaft from said rotor axis, and devices for imparting complete and continuous rotation to the cam carrying shafts and the rotor during each seaming operation.
2. In a seaming head structure of the character described, a chuck surrounded by a guide groove following the contour of the chuck, a rotor rotatable about the chuck, a plurality of positioning levers each attached at its outer end to a shaft rockably mounted on the rotor for swinging movement about an axis which parallels the axis of the rotor, each said positioning lever carrying a roller at its inner end engaging in said guide groove, a seaming arm pivotally mounted intermediate its ends on each lever with the inner and outer ends of each said arm overlying the inner and outer ends of the respective lever, a seaming roll carried at the inner end of each arm for cooperation with said chuck, a rotary cam engageable with the outer end of each seaming arm and mounted on a cam shaft which is rotatably mounted on the rotor separate and apart from the rockably mounted shaft to which the positioning lever on which the particular seaming arm is mounted is attached and paralleling said rockably mounted shaft, the axes of both said shafts lying substantially in an arc struck from the center of the rotor, and devices for imparting complete and continuous rotation to the cam carrying shafts and the rotor during each seaming operation.
3. In a seaming head structure of the character described, a chuck surrounded by a guide groove following the contour of the chuck, a rotor rotatable about the chuck, a plurality of positioning levers each attached at its outer end to a shaft rockably mounted on the rotor for swinging movement about an axis which parallels the axis of the rotor, each said positioning lever carrying a roller at its inner end engaging in said guide groove, a seaming arm pivotally mounted intermediate its ends on each lever with the inner and outer ends of each said arm overlying the inner and outer ends of the respective lever, a seaming roll carried at the inner end of each

arm for cooperation with said chuck, a rotary cam engageable with the outer end of each seaming arm and mounted on a cam shaft which is rotatably mounted on the rotor separate and apart from the rockably mounted shaft to which the positioning lever on which the particular seaming arm is mounted is attached and paralleling said rockably mounted shaft, the axes of both said shafts lying side by side in the direction of rotation of the rotor and the cam shaft axis being spaced from the rotor axis a distance approximately the same as the distance of said rockably mounted shaft from said rotor axis, each rotary cam carrying shaft having rotative bearing in an eccentric bearing sleeve which is rotatably-adjustably mounted in the rotor, and devices for imparting complete and continuous rotation to the cam carrying shafts and the rotor during each seaming operation.

4. In a seaming head structure of the character described, a chuck surrounded by a guide groove following the contour of the chuck, a rotor rotatable about the chuck, four positioning levers pivoted at their outer ends at equidistantly spaced points on the rotor adjacent the periphery thereof and having rollers at their inner ends engaged in said groove, four shafts rotatably mounted on the rotor one beside and spaced apart from each lever pivot and spaced from the rotor center a distance not greater than the distance between the rotor center and each of said pivots,

each said shaft having a pinion gear on one end and a cam on the other and said cams being arranged in diametrically oppositely disposed first and second operation pairs with each first operation cam having three steps each followed by a dwell portion and each second operation cam having two steps each followed by a dwell portion, a seaming arm rockably mounted intermediate its ends on each lever and having a large roller rotatably mounted thereon at one end engaged by the adjacent cam and a seaming roll at its other end movable against the chuck by roller and cam engagement, and devices for imparting continuous rotation to the rotor and simultaneously to all said pinion gears.

10 15 OTTO A. SCHMITT.
